UNITED STATES PATENT OFFICE.

BERNARD RIVERA KABIGTING, OF SANTA BARBARA, CALIFORNIA.

SLEEVE AND CUFF HOLDER.

1,199,565.

Specification of Letters Patent. Patented Sept. 26, 1916.

Application filed January 14, 1916. Serial No. 72,092.

To all whom it may concern:

Be it known that I, BERNARD RIVERA KABIGTING, a citizen of the United States, residing at Santa Barbara, in the county of 5 Santa Barbara and State of California, have invented certain new and useful Improvements in Sleeve and Cuff Holders; and I do hereby declare the following to be a full, clear, and exact description of the invention, 10 such as will enable others skilled in the art to which it appertains to make and use the same.

This invention relates to sleeve or cuff holders, and the primary object of the invention is to provide a holder for cuffs or 15 shirt sleeves, which will hold the marginal edges of the cuffs or sleeves properly connected and maintain the proper shape of the cuffs.

20 Another object of this invention is to provide a cuff or sleeve holder as specified which includes a substantially V-shaped member for engagement with the outer surfaces of a cuff adjacent to its marginal edges, and an 25 adjustable member which is positioned within the cuff and is adjustable for forcing portions of the cuff against the inner sides of the V-shaped member for securely clamping the holder to the cuff or sleeve and maintaining the cuff in its proper shape.

30 With the foregoing and other objects in view this invention consists in such novel features of construction, combination and arrangement of parts as will be hereinafter 35 more fully described, illustrated in the accompanying drawings and claimed.

In describing the invention in detail reference will be had to the accompanying drawings wherein like characters designate 40 like and corresponding parts throughout the several views, and in which:—

Figure 1 is a perspective view of a fragment of a shirt cuff showing the improved holder attached thereto, Fig. 2 is a perspective view of the holder, Fig. 3 is a sectional view through the holder showing it applied to a shirt cuff, Fig. 4 is a side elevation of the holder showing parts thereof broken away, Fig. 5 is a section on the line 5—5 of Fig. 4, and Fig. 6 is a detail view showing the manner in which a cuff must be cut to permit of the attachment of a holder thereto.

Referring more particularly to the drawings, 1 and 2 designate the free edges of a 55 shirt cuff of ordinary construction, which

are provided with recesses 3 cut therein and extending inwardly from their marginal edges.

The holder includes, a substantially V-shaped plate 4 which comprises a pair of upstanding diverging plates 5 and 6 which have their edges connected by a bight portion 7 the inner surface of which is adapted for lying in a horizontal plane. The plates 5 and 6 curve, to conform to the curvature 60 of the cuff 1. In applying the sleeve or cuff holder, the plates 5 and 6 are positioned upon the outer surfaces of the edges of the cuff, while the bight portion 7 extends across from one end to the other within the recess 3. 70 An adjustable structure generically indicated by the numeral 10 is positioned interiorly of the cuff, and is adapted for forcing the sides of the cuff outwardly into engagement with the inner surfaces of the 75 plates 5 and 6 for properly connecting the holder to the cuff. The structure 10, comprises a substantially T-shaped member 11, which has a head 12, the edges of which are provided with a plurality of recesses 13, for 80 providing a roughened edge for engagement with the shirt cuff. The base 14 of the member 11 is hollow, and is also provided with a pair of vertically extending openings 15 and 16 which communicate with the interior 85 of the post or base 11. The head 12 is provided with an opening 17 extending vertically through the center of the same which has an enlargement 18 formed therein. A bolt 19 extends through the opening 17, and 90 it has an enlargement 20, formed thereon which is rotatably seated in the enlargement 18 of the opening 17. The bolt 19 has an eye at 21 formed upon its upper end and projecting outwardly out of the head 12. A plate 22 is loosely connected to the eye 21 and lies in abutment with the upper surface of the head 12, when not in use and when it is desired to rotate the bolt 19, the plate 22 is moved vertically so that it can be conveniently gripped by the thumb and finger of an operator for rotating the bolt.

The screw threaded shank 23 of the bolt 19 is seated in a screw threaded opening 24 which extends vertically within an enlarged portion 25 formed centrally in the member 26. The member 26 comprises a plate 27 which is vertically adjustable within the hollow portion of the post 14 of the member 11, and a transversely extending plate 28 110

which is attached to the lower edge of the plate 26 and engages the upper flat surface of the bight portion 7, as is clearly shown in Figs. 2 and 3 of the drawings. The edges 5 of the transverse plate 28 are positioned beneath the longitudinal edges of the recesses 3 which are formed within the cuff.

When the improved holder is attached to the free edges of a cuff or sleeve for holding 10 these edges in their proper positions and facilitating the maintenance of the proper shape of the cuff, the V-shaped member 4 is positioned so that the plates 5 and 6 will engage the outer surfaces of the edges 1 15 and 2 of the cuff and so that the bight portion 4 will extend through the recesses 3. The adjustable member 10 is positioned within the cuff between the edges 1 and 2, so that the horizontal or transverse plate 20 28, will rest upon the upper horizontal surface of the bight portion 7, and be positioned beneath the longitudinal edges of the recesses 3, as is clearly shown in Fig. 3 of the drawings. After the member 10 has 25 been positioned in this manner, the bolt 19 is rotated which will feed the upper T-shaped section or member 12 downwardly causing the edges of the head of the same to engage the inner surfaces of the sides or 30 edges 1 and 2 of the cuff and force them into firm binding engagement with the inner surfaces of the plates 5 and 6, thereby securely attaching the holder to the cuff or 35 shirt sleeve and also cause the holder to connect the free edges of the cuff or sleeve.

In reducing the invention to practice, certain minor features of construction, combination and arrangement of parts may necessitate alterations to which the patentee 40 is entitled provided such alterations are comprehended within the scope of what is claimed.

What is claimed is:—

1. In a cuff or sleeve holder, the combination, of a substantially V-shaped member 45 including a pair of diverging side plates, a

bight portion connecting the lower edges of said plates, a body plate having a substantially horizontally positioned plate formed 50 upon its lower edge, said horizontally positioned plate positioned upon the inner surface of said bight portion, a sleeve formed centrally of said body plate and extending vertically thereon, a substantially T-shaped 55 member adjustably supported by said plate, the edges of the head of said substantially T-shaped member being provided with a plurality of notches, the edges of said T-shaped member adapted for engagement with the inner surfaces of the portions of a cuff or sleeve 60 adjacent to its marginal edges for forcing them into firm engagement with the inner surface of said diverging side plates.

2. In a cuff or sleeve holder, the combination, of a substantially V-shaped member including a pair of diverging side plates, a bight portion connecting the lower edges of said plates, a body plate having a substantially horizontally positioned plate formed 70 upon its lower edge, said horizontally positioned plate positioned upon the inner surface of said bight portion, a sleeve formed centrally of said body plate and extending vertically thereon, a substantially T-shaped 75 member adjustably supported by said plate, the edges of the head of said substantially T-shaped member being provided with a plurality of notches, the edges of said T-shaped member adapted for engagement 80 with the inner surfaces of the portions of a cuff or sleeve adjacent to its marginal edges for forcing them into firm engagement with the inner surface of said diverging side plates, a bolt rotatably supported by said plate, a T-shaped member and being adjustably 85 mounted within said sleeve for moving said T-shaped member vertically upon the rotation of the bolt.

In testimony whereof I affix my signature 90 in presence of two witnesses.

BERNARD RIVERA KABIGTING.
